(Cl. D72—1)

FIG. 1.

FIG. 2.

Figure 1 is a front elevational view of a marker light for highways or the like, showing our new design; and Figure 2 is a side elevational view thereof.

The rear of the marker light for highways or the like, which is not shown, is substantially the same in appearance as the front, and the side not shown is substantially the same in appearance as the side shown.

We claim:

The ornamental design for a marker light for highways or the like, substantially as shown and described.
